United States Patent

Des. 237,830
Patented Nov. 25, 1975

237,830

COPYING MACHINE

John James Van Acker, Chesterland, Ohio, and Jordan I. Rotheiser, Highland Park, Ill., assignors to Addressograph-Multigraph Corporation, Cleveland, Ohio

Filed Aug. 12, 1974, Ser. No. 496,691

Term of patent 14 years

Int. Cl. D16—03

U.S. Cl. D61—1 Q

Fig. 1

Fig. 2

FIG. 1 is a perspective view showing the front and right side panel of a copying machine showing our new design;

FIG. 2 is a top plan view thereof;

FIG. 3 is a right side elevation thereof;

FIG. 4 is a front elevation thereof; and

FIG. 5 is a left side elevation thereof.

We claim:

The ornamental design for a copying machine, substantially as shown.
